E. CRAIG

WIRE TWISTER

Filed Sept. 17, 1924

Inventor:
Edward Craig
By Arthur F. Durand

UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

WIRE TWISTER.

Application filed September 17, 1924. Serial No. 738,125.

This invention relates to twisters in general, but more particularly to those for twisting the ends of the wire together on the corners of wire bound boxes, after the boxes are filled, so that the boxes will be tightly closed.

Generally stated, the object of the invention is to provide a novel and improved form of wire twister, whereby the twister may be used for closing wire bound boxes in the usual manner, by twisting the ends of the wire together, or for other purposes, and whereby it will not be necessary to employ certain mechanical features and methods heretofore considered necessary in the construction and use of a twister for this purpose.

Another object is to provide an improved wire twister of such character that it will not be necessary to press down on the box, while twisting the wire, as will hereinafter more fully appear.

Another object is to provide a novel and improved construction whereby the wire will be cut off after the twist is made, so that excess wire will not be left on the end of the twist.

It is also an object to provide certain details and features of construction and combinations tending to increase the general efficiency and the desirability of a wire twister of this particular character.

To the foregoing and other useful ends the invention consists in matters hereinafter set forth and claimed and shown in the accompanying drawings in which:

Fig. 1 is a side elevation of a wire twister embodying the principles of the invention, showing the same applied for twisting together the ends of the wire of a wire bound box.

Fig. 2 is an enlarged side elevation of the gripping portion of the tool shown in Fig. 1, showing two end portions of the wire gripped and held in place.

Fig. 3 is a view similar to Fig. 2, but showing the jaws of the twister separated to release the wire.

Fig. 4 is a front end elevation of the mechanism shown in Fig. 3.

Fig. 5 is a detail view showing the completed twist formed by using the twister on

the ends of the wire encircling the wire bound box.

As thus illustrated, the invention comprises a head or body portion 1, the rear end portion of which is provided with a handle 2, and with a crank handle 3, like an ordinary brace and bit, so that the twister can be rotated to twist the wire. The jaw 4 is rigid with the head 1 and has a beveled engaging surface 5 as shown. The jaw 6 is held on the head by a pivot screw 7, as shown, and has a flat engaging surface 8 to engage the wire, as shown. A short hand lever 9 is pivoted by a screw 10 on the head 1, and a link 11 is pivoted at 12 and 13 on the lever 9 and the jaw 6, respectively, whereby said jaw is connected for oscillation about its pivot formed by the screw 7, in an obvious manner, by movement of the lever 9 up or down. A stop 14 on the lever 9 engages the under side of the head to limit the upward movement of the lever 9, so that the pivotal point 12 is just about on center, or a little past center, when the two jaws are closed upon the wire.

Thus, when the wires are gripped, the end portions are turned or bent at an angle, by the gripping surfaces 5 and 8 of the two jaws. When the hand lever 9 is moved into the position shown in Figs. 1 and 2, it will automatically stay in this position, inasmuch as the pivot 12 is on center, or a little past the center, and the wires will remain gripped in the manner shown. By revolving the crank handle 3, which is like an ordinary carpenter's brace for rotating a bit, the twister head will be rotated and this will twist the wire into the condition shown in Fig. 5 of the drawings. The twist progresses from the tool toward the box, it will be seen, instead of from the box outwardly, whereby the end portions of the wire which are clamped by the twister will be cut or twisted off as soon as the twist has been completed and has reached the box.

Thus it is not necessary to bear down upon the box, in the twisting of the wire, but to the contrary the operator pulls back on the twister, if anything, and the wire is cut off by the jaws which clamp and twist the wire, after the twist is formed. Thus the surplus wire ends are cut off at the end of the twist.

ing operation, and after the twist is made, and the two cut off portions of the wire are then released by throwing the hand lever 9 into the position shown in Fig. 3 of the drawings.

It will be seen that the entire device thus provided for twisting wires together is exceedingly simple, and is comparatively inexpensive to manufacture, and is simple and effective in its operation, so that the wires can be quickly clamped and held, in such a manner that the twister can then be rotated without danger of releasing the wires.

During the twisting operation, it will be seen that the axis of rotation is substantially in line or coincident with the line of pull exerted on the wire, inasmuch as the user can pull back somewhat, if necessary, during the twisting operation. The twist progresses from the tool toward the box, substantially in line with the line of pull exerted on the tool during the twisting operation, and with the end portions of the wire bent at an angle to said line of pull, in the manner shown and described.

Thus it will be seen that the wires are gripped between the surfaces 5 and 8, which are flat, and which extend rearward a distance from the cutting edge of the jaw 6. Thus the wires are clamped a substantial distance back from the point where they are severed or cut off, but are free to run together as the twist progresses and tightens up against the twister. Moreover, with the clamping surfaces 5 and 8 disposed at an angle, as shown, the wires are bent back and forth while the twister is being rotated, so that the wires are weakened at a point close to the sharp end edge of the jaw 6, whereby the wires are readily broken or cut off as soon as the twist is completed. The surface 5, it will be seen, is in the nature of the bottom of a straight notch formed in the lower end of the jaw 4, so that the jaw 6 moves into this notch to grip the wires, and the latter are held against displacement from between the jaws. There is space back of the jaws for the loose ends of the wires, if they are somewhat longer than the twist desired, and the front edges of the two jaws can be placed exactly at the point on the wires where the severing or cutting operation is to be performed, after the twist is completed, so that the twist may be of the desired length. But, as shown and described, the wires are effectively held between flat surfaces for a substantial distance back from the cutting or severing point, and a substantial distance back from the cutting edge of the lower pivoted jaw. This tends to ensure the desired twisting action, and tends to insure the cutting or breaking off of the wires, in the manner described, after the twist is fully completed.

What I claim as my invention is:—

1. In a wire twister, a head having relatively movable gripping and cutting jaws provided with a cutting edge at the extreme outer end of the jaws, for cutting the wire, and with opposing faces for gripping the end portions of the wire, so formed that the wire is clamped between the jaws, at an angle to the axis of the twist, and instrumentalities for manually rotating said head, whereby the twist progresses away from the tool and entirely in sight, and devices for manually controlling the relative closing movement between said jaws, by which the jaws are positively brought together manually to grip the wire between the flat opposing faces thereof, carried by said head.

2. A structure as specified in claim 1, said jaws being pivoted together and adapted to grip the wire and formed to bend it at said angle to the axis of rotation, so that the end portions of the wire are disposed at an angle to the line of pull, and so that the end portions are automatically cut off at the outer end of the twist and at the outer meeting edges of the jaws when the twist is completed.

3. A structure as specified in claim 1, said devices comprising toggle connections having a toggle joint which is straightened and thereby brought into position to automatically hold the jaws together, when the wire is clamped between them, so that the one jaw which is movable is self-locking in operative position.

4. A structure as specified in claim 1, said devices comprising a hand lever pivoted on the head, a pivot for one of said jaws, whereby this jaw is movable relatively to the other jaw, and a link connecting said hand lever with said pivoted jaw, forming a toggle connection having a joint which has a position to hold the movable jaw in operative position, when the wire is clamped between the jaws, whereby the movable jaw is self-locking in operative position.

5. A wire twister tool comprising gripping jaws and means for rotating them about a longitudinal axis substantially coincident with the line of pull exerted on the wire during the twisting operation, said jaws being formed and disposed in position to bend the end portions of the wire at an angle to the said axis and line of pull, and one jaw being pivoted and having a sharp outer edge engaging the wire at the angle of said bend, preventing the twist from extending between said jaws so that the twist is entirely in sight.

6. A wire twister tool for twisting together the ends of the wire on wire bound boxes, comprising twisting means operative to complete the twist and having a cut off edge at the end thereof adapted thereafter to automatically cut off the untwisted end portions of the wire, preventing the twist

from extending between said jaws, so that the twist is entirely in sight.

7. In a wire twister tool, a head having jaws for gripping the end portions of the wire, and instrumentalities for rotating said head, whereby the twist progresses away from the tool, and devices for controlling the relative movement between said jaws, carried by said head, said jaws being pivoted together and formed to grip the wire and bend the extreme end portions thereof at an angle to the axis of rotation of said head, so that the untwisted end portions of the wire are disposed at an angle to the line of pull, and having a cut off edge so that said end portions are automatically cut off when the twist is completed, preventing the twist from extending between said jaws, so that the twist is entirely in sight.
- 10 8. In a wire twister, a head having relatively movable jaws for gripping the end portions of the wire, and instrumentalities for rotating said head, whereby the twist progresses away from the tool, and devices for controlling the relative movement between said jaws, carried by said head, said

devices comprising toggle connections having a toggle joint which has a straightened position to automatically hold the jaws together, when the wire is clamped between them, so that by said position one jaw which is movable is self-locking in operative position.

9. In a wire twister, a head having jaws for gripping the end portions of the wire, and instrumentalities for rotating said head, whereby the twist progresses away from the tool, and devices for controlling the relative movement between said jaws, carried by said head, said devices comprising a hand lever pivoted on the head, a pivot for one of said jaws, whereby this jaw is movable relatively to the other jaw, and a link connecting said hand lever with said pivoted jaw, forming a toggle connection having a position to hold the movable jaw in operative position, when the wire is clamped between the jaws, by which toggle the movable jaw is self-locking in operative position.

Specification signed this 13th day of Sept., 1924.

EDWARD CRAIG.
